CHILD'S FLEXION WHEELCHAIR

Thomas R. Blue, 17802 Norwood Park,
Tustin, Calif. 92680

Filed Nov. 18, 1974, Ser. No. 524,787

Term of patent 14 years

Int. Cl. D12—12

U.S. Cl. D12—131

FIGURE 1

FIGURE 2

FIGURE 3

FIG. 1 is a front perspective view of a child's flexion wheelchair showing my new design;

FIG. 2 is a rear perspective view thereof; and

FIG. 3 is a bottom perspective view thereof with the footrest portion pivoted to a different position for clarity of illustration.

I claim:

The ornamental design for a child's flexion wheelchair, as shown and described.
